US00D738036S

(12) **United States Design Patent**
Tucker et al.

(10) **Patent No.:** US D738,036 S
(45) **Date of Patent:** ** Sep. 1, 2015

(54) **ELECTRONIC SMOKING ARTICLE**

- (71) Applicant: **Altria Client Services Inc.**, Richmond, VA (US)
- (72) Inventors: **Christopher S. Tucker**, Midlothian, VA (US); **Geoffrey Brandon Jordan**, Midlothian, VA (US); **Barry S. Smith**, Hopewell, VA (US); **Ali A. Rostami**, Glen Allen, VA (US)
- (73) Assignee: **ALTRIA CLIENT SERVICES INC.**, Richmond, VA (US)
- (**) Term: **14 Years**
- (21) Appl. No.: **29/511,887**
- (22) Filed: **Dec. 15, 2014**

Related U.S. Application Data

- (62) Division of application No. 29/469,741, filed on Oct. 14, 2013, now Pat. No. Des. 722,196, which is a division of application No. 29/443,134, filed on Jan. 14, 2013, now Pat. No. Des. 691,765.
- (51) **LOC (10) Cl.** 27-01
- (52) **U.S. Cl.** **D27/101**
- (58) **Field of Classification Search**

(57) **CLAIM**

The ornamental design for an electronic smoking article, as shown and described.

DESCRIPTION

FIG. 1 is a perspective view of an electronic smoking article showing our new design.

FIG. 2 is side elevational view thereof, the other side being a mirror image; and,

FIG. 3 is an end elevational view thereof.

1 Claim, 2 Drawing Sheets

US D738,036 S
